UNITED STATES PATENT OFFICE.

CHARLES O. MATHEWS, OF DEVON, CONNECTICUT.

DESIGN FOR AN AUTOMOBILE SIGNAL LAMP.

Application filed February 14, 1924. Serial No. 8,637. Term of patent 3½ years.

To all whom it may concern:

Be it known that I, CHARLES O. MATHEWS, a citizen of the United States, residing at the town of Devon, in the county of New Haven and State of Connecticut, have invented a new, original, and ornamental Design for Automobile Signal Lamp, of which the following is a specification, reference being had to the accompanying drawing, forming part thereof, and in which

Figure 1 is a front elevation of an automobile signal lamp showing my new design.

Figure 2 is a perspective view.

I claim:—

The ornamental design for an automobile signal lamp, as shown.

CHARLES O. MATHEWS.
